CLAIM

The ornamental design for an earphone with charging case, as shown and described.

DESCRIPTION

FIG. 1 is a front, left and bottom perspective view of an earphone with charging case, shown separately to show aspects of the design that are not visible when combined, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left and bottom perspective view of a case of the earphone with charging case, shown separately to show aspects of the design that are not visible when combined, showing my new design;

FIG. 10 is a rear, and right perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof; and,

FIG. 17 is a front, left and bottom perspective view of the earphone with charging case shown combined.

The broken lines shown in the drawings illustrate portions of the earphone with charging case that form no part of the claimed design.
